CONSTANT-AREA VECTORING NOZZLE

Our invention relates to jet nozzles for reaction engines with means for varying the direction of the propulsive or lift jet. Such vectoring nozzles are frequently used as a means of control of aerial and space vehicles. Our invention is particularly suitable for deflection of the jet of vertical lift engines such as are used in certain types of vertical takeoff aircraft. In such installations, it may be desired to vector the jet from lift engines to control the aircraft in yaw or to translate it. In such an installation, it is important that the flow characteristics of the nozzle remain constant during such vectoring to avoid possible disturbance of the operation of turbojet lift engines which are vectored; and thus promote stability of the aircraft, or at least simplification of the controls.

The principal objects of our invention are to provide a vectoring nozzle which has a converging characteristic and which has a constant nozzle area during variations in direction of the jet; one which is simple in structure, and one which is of minimum weight and of conservative axial length with respect to the size of the jet engine and the angle of deflection of the jet. A more specific object of our invention is to provide a variable jet nozzle having three vanes swinging about substantially parallel axes which are so interconnected that they move together to deflect the engine exhaust or lift jet in either direction and provide a convergent nozzle of constant area over the range of deflection.

The nature of our invention and the advantages thereof will be clear to those skilled in the art from the succeeding detailed description of the preferred embodiment of the invention and the accompanying drawings thereof.

FIG. 1 is an elevation view of the jet nozzle for a jet engine with a vectoring arrangement according to our invention.

FIG. 2 is a transverse sectional view of the deflecting vanes taken on the plane indicated by the line 2—2 in FIG. 3; and

FIG. 3 is a bottom view of the nozzle.

The drawings illustrate only the lower or exhaust end of the lift engine, the remaining structure of which may be of any suitable type such as those shown in U.S. Pat. Nos. 3,263,420 and 3,313,105. The engine includes outer casing 5 which may be a turbine case or an exhaust duct therefrom, and which is cylindrical; a transition duct section 6 extending from casing 5 to a rectangular terminal portion 7 of the exhaust duct. The terminal portion 7 is bounded by two parallel walls 9 and by two diverging flat walls 10. An outer vane 11 (FIGS. 2 and 3) is mounted on a shaft 13 adjacent each outer wall 10. The vanes and shafts 13 are carried by hinge structures 14 extending from the jet nozzle and from the vanes 11. An inner vane 15 is fixed to a shaft 17 midway between the shafts 13, and the shaft is journaled in bosses 18 on walls 9. The solid line representation of vanes 11 and 15 in FIG. 2 shows their position for straight or nondeflected exhaust and the broken lines represent the position of the three vanes for maximum deflection of the jet, 20° in the particular case illustrated. The vanes may, of course, swing correspondingly in the opposite direction to deflect the jet 20° in that direction. It will be noted that the vanes converge toward each other so that, in the straight position, the nozzle is entirely converging with the throat at the trailing edge of the vanes, there being actually a throat at each side of vane 15. When the vanes are deflected as shown, there is a throat between the trailing edge of vane 15 and the side of the vane 11 which is swung outwardly and between the trailing edge of the vane 11 which is swung inwardly and the side of vane 15. The vanes 11 converge toward the trailing edge from the axes of rotation 13 of the vanes, and the shafts 13 are preferably parallel.

It is an important feature of our invention that the vanes are so coupled that the throat areas remain substantially constant throughout the range of travel of the vanes. This may be accomplished by a suitably constructed linkage interconnecting the vanes, the preferred embodiment of which is illustrated principally in FIG. 1. Shaft 13 of the left outer vane as illustrated is rigidly connected to an actuating arm 21 which, in turn, is coupled to a link 22 by a pivot pin 23. Pivot pin 23 lies

in the plane of vane 11. Link 21 is connected to the upper end of a rocker arm 25 by a hinge pin 26. Rocker arm 25 is supported by a shaft 27 mounted in a rocker arm support bracket 29 affixed to the wall 9. In the undeflected position of vane 15, the rocker arm 25 is disposed parallel to the axis of the nozzle. Pivot pin 26 also is coupled to a link 31 in turn pivoted by a pin 32 to a bellcrank 33 affixed rigidly to shaft 13 of the right hand outer vane as illustrated. Pin 32 lies in the plane of this vane. One arm of bellcrank 33 is coupled to the piston rod 34 of an actuating cylinder 36 which is mounted on a bracket 37 fixed to the exhaust duct 5.

The linkage so far disclosed will cause concurrent actuation of the two outer vanes in the same direction, but not to the same degree, as appears from FIG. 2. The remainder of the linkage comprises means for causing the intermediate vane to move to such extent as to maintain equality of the two outlets on each side of vane 15. This linkage should cause vane 15 to move in an amount approximately equal to the average of the movement of the outer vanes. In one simple and preferred form of the linkage to operate vane 15, it comprises an arm 40 rigidly fixed to rocker arm 25, an arm 41 rigidly fixed to the outer end of shaft 17, these arms being substantially parallel in the centered position of vane 15, and a link 42 pivoted to the ends of arms 40 and 41 coupling them for joint movement. With the linkage illustrated, rocker arm 25 swings in the opposite direction from arm 21 and bellcrank 33 and to a somewhat greater extent, as it is shorter. The linkage connecting arm 25 to shaft 17 acts as a reversing linkage so that arm 41 moves in the same direction as arm 21 and bellcrank 33. Arm 41 is longer than arm 40 so that the movement of vane 15 is less than that of rocker arm 25. By proportioning the linkage as shown and described, the movement of vane 15 will be approximately the average of the movement of the two outer vanes 11 and the constants may be chosen such that the width of the throats between the two outer vanes and the inner vane remain substantially the same in all positions of the vanes, and both nozzles remain convergent at all times.

It will be apparent from FIG. 3 that the operating and interconnecting linkage is duplicated at the other end of the vanes so as to provide the proper accuracy of movement with the rather light structure. The advantages of the arrangement will be apparent if we consider, for example, two vertical lift engines in an aircraft in which it is desired to vector the exhaust of one engine, either to control the aircraft in yaw, or to provide a forward and backward or a lateral control of aircraft movement. With the structures illustrated, the areas of the nozzles remain constant during the vectoring so that the performance of the engines is not differentially affected or compromised and lift of both engines will remain the same, other conditions remaining constant. The lift is not disturbed by the vectoring of the nozzle except to the extent that the lateral vector detracts from the vertical vector which, of course, will be the same for any two engines with the same degree of deflection.

The detailed description of the preferred embodiment of the invention for the purpose of explaining the principles thereof is not to be considered as limiting or restricting the invention since many modifications may be made by the exercise of skill in the art within the principles of the invention.

We claim:

1. A jet nozzle vectoring arrangement for a reaction engine comprising, in combination, an exhaust duct terminating in a portion of substantially rectangular cross section, two outer jet deflecting vanes pivotally mounted on means defining substantially parallel axes at opposite sides of the said portion, an inner jet deflecting vane pivotally mounted on means defining an axis substantially equally spaced from the outer vane axes, 65 the inner vane dividing the exhaust duct into two substantially rectangular convergent nozzles each having a throat bounded at opposite sides by a said outer vane and the inner vane, an actuator for swinging the three said vanes concurrently about their respective axes to deflect the jet, and a linkage connect- 70 ing the actuator to the three vanes for concurrent unequal 75

movement, the linkage being so constructed that both said nozzles remain convergent and of substantially constant area over the range of movement of the vanes.

2. A combination as recited in claim 3 in which the linkage comprises outer vane arms coupled to each outer vane swing-

ing about the pivot axes of the vanes, a rocker arm intermediate the outer vane arms, rotating counter to the outer vane arms, links connecting each outer vane arm to the rocker arm, and means coupling the rocker arm to the inner vane.

UNITED STATES PATENT OFFICE
CERTIFICATE OF CORRECTION

Patent No. 3,640,469 Dated February 8, 1972

Inventor(s) Charles F. Hayes and David R. Steffey

It is certified that error appears in the above-identified patent and that said Letters Patent are hereby corrected as shown below:

Column 3, line 4, "claim 3" should read -- claim 1 --.

Signed and sealed this 21st day of November 1972.
